UNITED STATES PATENT OFFICE.

WILBERT C. TRUSSELL, OF BOSTON, AND HENRY F. SAWTELLE, OF LEOMINSTER, MASSACHUSETTS.

HYDRAULIC MOTOR.

SPECIFICATION forming part of Letters Patent No. 660,131, dated October 23, 1900.

Application filed February 8, 1900. Serial No. 4,498. (No model.)

To all whom it may concern:

Be it known that we, WILBERT C. TRUSSELL, of Boston, in the county of Suffolk, and HENRY F. SAWTELLE, of Leominster, in the county 5 of Worcester, State of Massachusetts, have invented certain new and useful Improvements in Hydraulic Motors, of which the following, taken in connection with the accompanying drawings, is a specification.

10 This invention relates to hydraulic motors, and has for its object the obtaining of a rotary motion from the rectilinear movements of a hydraulic jack; and it consists in certain novel features of construction, arrangement, 15 and combination of parts, which will be readily understood by reference to the description of the accompanying drawings and to the claims hereto appended, and in which this invention is clearly pointed out.

20 Figure 1 of the drawings is a plan of a motor illustrating the invention. Fig. 2 is a longitudinal section on line A A on Fig. 4. Fig. 3 is a front elevation of the same. Fig. 4 is a sectional elevation, the cutting-plane being 25 on line B B on Fig. 3 looking toward the left of said figure. Fig. 5 is a partial sectional elevation on line C C on Figs. 1 and 2 looking toward the right of said figures, drawn to an enlarged scale, and illustrating the valve-re- 30 versing mechanism. Fig. 6 is an elevation of the clutch end of one of the shaft-inclosing sleeves with the grip-rolls in position on the shaft to be driven, which is shown in trans- 35 verse section. Fig. 7 is an elevation of the opposite end of said sleeve with the shaft re- 40 moved. Fig. 8 is a longitudinal section of said sleeve with the shaft and grip-rolls removed. Fig. 9 is a longitudinal section of the valve-casing and a small portion of the 45 plug-valve, the cutting-plane being on line D D on Fig. 5. Fig. 10 is a section of the same parts on line E E on Fig. 5. Fig. 11 is a transverse section through valve and valve- 50 casing on the crooked line F F on Fig. 10, and Fig. 12 is a similar section on line G G on Fig. 9.

In the drawings, 1 is the shaft to which it is desirable to impart a rotary motion about its axis, said shaft being mounted in bearings 50 in the stands 2 and 3, as shown. Said shaft has mounted thereon so as to be revoluble

therewith or independently thereof the two sleeves 4 and 5, each having formed in its end contiguous to the shaft-supporting stand a chamber in the inner surface of the wall of 55 which is formed an eccentric surface 6, joining a radial surface 7, whereby a curved wedge-like pocket 8 is formed, in which is placed a hardened-steel roll 9, resting upon the shaft 1, said roll being of such a diameter that when resting against the radial surface 7 it will have no grip upon the shaft; but as soon as the sleeve is moved in the direction indicated by the arrow on Fig. 6 said roll is wedged between said shaft and the surface 6 and the shaft is compelled to move 60 with the sleeve.

The sleeves 4 and 5 are made rights and lefts, or so that whether the power is applied to one or the other of said sleeves the shaft 70 will revolve in the same direction.

Any desired number of pockets formed by the surfaces 6 and 7 in the clutch-head of the sleeves 4 and 5 and of the rolls 9 may be employed in each sleeve, though the drawings 75 show four pockets in each clutch-head. Each sleeve has secured thereon near the middle of its length a collar 10, so as to be revoluble therewith. Two stands 11 and 12, each provided with a bearing for one of said sleeves 80 and a recess to receive the collar 10, are arranged as shown, and each has formed in one piece therewith a plurality of cylinders 13, arranged radially to the axis of shaft 1, having their outer ends open and each communicat- 85 ing at its inner end with the segmental chamber 14, which extends about three-fourths (more or less) around said shaft 1 at the same distance therefrom as the inner ends of the bores of said cylinders, as shown in Figs. 2 90 and 4.

The casting of each stand 11 and 12 has formed therein a chamber 15, which is provided with an opening 16, as shown in Figs. 2 and 4. 95

Each cylinder 13 has fitted thereto a piston 17, the outer end of which is forked and has mounted therein a sheave 18 and has secured to its inner end a suitable cup-packing 19, as shown.

A chain 20 is firmly secured by one end to the sleeve 4 at 21 within the chamber 15,

passes out of said chamber through the opening 16, under the pulley 22, over the pulley 23, partially around each of the sheaves 18 in the outer ends of the pistons mounted in the 5 several cylinders formed in the stand or frame 11, over the pulleys 24 and 22, through the passage 16 into the chamber 15, and has its other end secured to the collar 10 on the sleeve 4, the bolts for securing the two ends of said 10 chain to said sleeve having their axes parallel to the axis of said sleeve and its shaft and may be in the same or different axial lines, but at equal distances from the axis of the shaft. A similar chain 25 is mounted in ex- 15 actly the same manner upon the sheaves 18, carried by the pistons mounted in the cylinders formed on the stand or frame 12, and has its two ends secured to the sleeve 5 in the same manner as the chain 20 is secured to the 20 sleeve 4.

The pulleys 22, 23, and 24 are mounted on and revolve freely about the stud-bolts 26, 27, and 28, as shown in Figs. 1, 2, and 4.

The inner end of the sleeve 4 has firmly se- 25 cured thereon the bevel gear-wheel 29, which engages the bevel-pinion 30, mounted upon a fixed stud 31, set in the stand 32, which pion- 30 ion in turn engages the bevel gear-wheel 33, firmly secured upon the inner end of the sleeve 5, as shown in Figs. 1 and 2, by which ar- 35 rangement of connecting-gearing the sleeves 4 and 5 always revolve in opposite directions, whereby when one chain is being unwound from its sleeve, which is always at such times 40 coupled to the shaft 1, the other chain is be- 45 ing wound upon its sleeve, which is at that time uncoupled from said shaft and is being rotated in the opposite direction to that of said shaft.

40 A plate 34, nearly triangular in shape, is bolted to the outer surfaces of the two upper cylinders of each frame 11 and 12 or opposite the stay-ribs 35, in which plates and ribs are set in fixed positions the stud-bolts 26, 27, 45 and 28, as shown.

45 A pipe 36 leads from the right-hand chamber 14 to the chamber 37, secured to the upper side of the valve-casing 38, and a similar pipe 39 leads from the left-hand chamber 14 to the chamber 40, formed in the same casting with the chamber 37, which is secured to the upper flat surface of said casing 38. (See Fig. 9.)

The valve-casing 38 has four pairs of trans- 55 verse openings or ports 41, 42, 43, and 44 ex- 60 tending therethrough and has fitted therein a plug-valve 45, having four transverse perforations 46, 47, 48, and 49 extending through the same so arranged relative to the openings 65 in said casing that when said valve is in the position shown in the drawings the passages 47 and 49 through said valve shall coincide with the passages 42 and 44, respectively, and when said valve is moved about its axis in 70 the direction indicated by the arrow 77 on Fig. 5 to the limit of its movement in that direction the passages 46 and 48 through said

valve will coincide with the ports 41 and 43, respectively, through said casing. The pas- 75 sages 42 and 43 in said casing are covered at their upper ends by a casting containing the chambers 37 and 40 and at their lower ends by the casting 50, having the chamber 51, with which one end of a pipe 52 communicates, as shown in Figs. 9 and 12. Said pipe 52 extends 75 from said chamber 51 to and communicates with a chamber in the base of the double-acting force-pump 53, in which the pistons 54 and 55 are operated by the three-armed hand- 80 lever 56 or in any other well-known manner. The interior construction of said pump not being new is not shown in detail, except that the space between the two cylinders forms a 85 tank or reservoir from which the liquid used in the cylinders 13 is drawn and to which it is returned after having forced the pistons 17 outward.

Any double-acting force-pump, either hand or power, may be used, according to the par- 90 ticular purpose for which the motor is to be used.

A discharge-pipe 57 leads from the cham- 95 ber 14 in the stand or frame 11 to and com- 100 municates with the interior of a chamber 58 in the casting 59, secured to the rear side of the valve-casing 38 and covering the port 44, through which and the passage 49 communi- 105 cation is had with the chamber 60, formed in the casting 61, secured to the front side of said valve-casing, from which the pipe 62 leads to and communicates with the reservoir 63 in the pump-casing. (Indicated by dotted lines in Fig. 4.) A discharge-pipe 64 leads from the chamber 14 in the stand or frame 12 to and communicates with the interior of the 110 chamber 65 in said casting 59, from which chamber communication is had with the cham- 115 ber 60 through the passages 41 and 46.

The gear-wheel 33 has secured thereto the disk 66, having formed upon its periphery a single tooth 67, constructed and arranged to act upon a tooth 68, carried by the rod 69, supported and guided by a suitable bearing beneath said tooth 68 and pivoted at its op- 120 posite end to the lower end of the lever 70, pivoted at 71 to a fixed part of the machine and engaging at its upper end the crank-pin 72 or a truck mounted thereon, set in the end of the plug-valve 45, as shown in Fig. 5.

The pump 53 is provided with an air-cham- 125 ber 73, constructed and arranged to operate in the usual well-known manner.

A tie-girth 74 connects the two frames 11 and 12 and supports the valve-casing 38, which is provided with the downwardly-projecting legs 125 75 and 76, which are firmly bolted to said tie- 130 girth 74, as shown in Figs. 1, 3, and 4.

The operation of this invention is as fol- 130 lows: The several parts of the machine being in the positions shown in the drawings—that is, with the set of pistons carried by the frame 11 moved outward and those carried by the frame 12 moved inward and the chain carried thereby wound upon the sleeve 5—if the res-

ervoir from which the pump is to draw its supply of suitable liquid is properly charged and power be applied to the pump the liquid will be forced through the pipe 52, chamber 51, passages 42 and 47, chamber 40, pipe 39, and the chamber 14 to the cylinders 13, carried by the frame 12, and will force the pistons 17 contained in said cylinders outward, thereby unwinding the chain 25 from the sleeve 5 and rotating said sleeve in the direction indicated by the arrow on Fig. 4, and the bevel gear-wheel 33 being firmly secured to said sleeve 5 and revolving therewith and acting through the bevel-pinion 30 upon the gear 29 causes said gear 29 and the sleeve 4 upon which it is secured to revolve in the opposite direction to that indicated by said arrow, and thus wind the chain 20 upon the sleeve 4, thereby moving the pistons carried by the frame 11 inward to the inner ends of their cylinders and forcing the liquid contained therein through the pipe 57, passages 44 and 49, and pipe 62 into the reservoir 63. The disk 66 revolves with the sleeve 5 in the direction indicated by the arrow 78 on Fig. 5 until it and said sleeve have made one complete revolution and the tooth 67 has come in contact with the tooth 68 on the bar 69 and moved it and the lever 70 into the positions indicated by dotted lines in Fig. 5, thereby rotating the plug-valve so as to close the passages or ports 42 and 44 and bring the passages 46 and 48 through said plug into axial line with the passages or ports 41 and 43, when the liquid will be forced by the pump through the pipe 52, chamber 51, passages 43 and 48, chamber 37, and pipe 36 into the chamber 14 in the frame 11 and into the cylinders 13, carried by said frame, and forcing the pistons therein outward, and unwinding the chain 20 from the sleeve 4 causes said sleeve to be rotated in the direction indicated by the arrow on Fig. 4, carrying with it the shaft 1, to which it is secured while moving in that direction by the action of the inclined surfaces 6 upon the grip-rolls 9. At the same time through the action of the gears 29, 30, and 33 the sleeve 5 is revolved upon said shaft in the opposite direction, thereby winding the chain 25 upon said sleeve and forcing the pistons acted upon by said chain inward, thereby forcing the liquid contained in said cylinders through the pipe 64, passages 41 and 46, chambers 65 and 60, and pipe 62 to the interior of the reservoir 63 to be used over again, during which backward rotation of the sleeve 5 the disk 66 makes a complete revolution in the reverse direction to that indicated by the arrow 78 on Fig. 5 and moves the rod 69 and the lever 70 into the positions shown in full lines in Fig. 5, thereby again reversing the direction of the flow of liquid from the pump and also the flow of the liquid from the chain-operating cylinders to the reservoir in the pumping casing. These operations may be continued indefinitely, the two sleeves alternately making one revolution forward and then one

backward, thereby causing a continuous revolution of the shaft 1 always in the same direction so long as the pump is operated. 70

A greater or less number of cylinders 13 may be used in connection with each sleeve 4 or 5, if desired, without departing from the principles of the invention.

We claim—

1. The combination of a shaft to be revolved; a sleeve mounted upon and revoluble about said shaft; a clutch mechanism constructed and arranged to automatically couple said sleeve to said shaft when moving in one direction, and to uncouple the same when moving in the opposite direction; a hydraulic-jack mechanism arranged in a fixed position radial to said shaft; a sheave carried by the outer end of the piston of said jack mechanism; a plurality of guide-pulleys arranged outside of said sleeve; a flexible connection extending about and bearing upon said sheave and pulleys and firmly connected to and wound about said sleeve; and means for forcing liquid into the cylinder of said jack mechanism to force said piston outward and thereby unwind said flexible connection from said sleeve and rotate said sleeve and shaft. 85

2. In a hydraulic motor, the combination 95 with the shaft to be revolved, of a sleeve mounted upon and revoluble about said shaft; a clutch mechanism constructed and arranged to automatically couple said sleeve to said shaft when moving in one direction, and to uncouple the same when moving in the opposite direction; a plurality of hydraulic cylinders arranged in fixed positions radial to the axis of said shaft, with open outer ends; a piston fitted to and movable 105 endwise in each of said cylinders; a sheave mounted upon a suitable journal-pin carried by each of said pistons; a plurality of guide-pulleys; a flexible connection extending about and bearing upon said several sheaves 110 and guide-pulleys and firmly connected to said sleeve and adapted to be wound upon and unwound from said sleeve; a curved chamber connecting the inner ends of said cylinders; and means for forcing a liquid 115 into said curved chamber, and thence to said cylinders to move said pistons outward and thus unwind said flexible connection from said sleeve and rotate said sleeve and shaft. 120

3. The combination with a shaft to be rotated, of a sleeve mounted upon and revoluble about said shaft, a clutch mechanism constructed and arranged to automatically couple said sleeve to said shaft when moving 125 in one direction, and to uncouple the same when moving in the opposite direction; a fixed frame provided with an opening for said sleeve, a chamber surrounding said sleeve with an outlet at one side, a plurality 130 of cylinders arranged radially to the axis of said shaft with open outer ends, and a segmental chamber connecting the interiors of all of said cylinders at their inner ends; a

piston fitted to and movable endwise in each of said cylinders; a sheave mounted in the outer end of each of said pistons; a plurality of guide-pulleys between two of said cylinders; a flexible connection, as a chain, extending about and bearing upon said sheaves and guide-pulleys and firmly connected to, and adapted to be wound upon said sleeve; a double-acting force-pump for forcing a liquid into said cylinders to move said pistons outward; a pipe connecting said pump with said segmental chamber; a discharge-pipe leading from said segmental chamber; and suitable valves for controlling the inlet and discharge of said liquid.

4. The combination of a shaft to be revolved; a pair of sleeves mounted end to end upon said shaft and revoluble thereon; a clutch mechanism carried by each of said sleeves and constructed and arranged to automatically couple its sleeve to said shaft to move it in one and the same direction, and uncouple the same when moving in the opposite direction; a train of gearing connecting said two sleeves, so that when one revolves in one direction the other will revolve in the opposite direction; a plurality of cylinders arranged around each of said sleeves in fixed positions and radial to the axis of said shaft and having open outer ends; a piston mounted in each of said cylinders and movable endwise therein; a sheave carried by the outer end of each piston; a plurality of guide-pulleys arranged between two of each set of said cylinders; a flexible connection, as a chain firmly secured to one of said sleeves and extending about and bearing upon the sheaves and pulleys surrounding said sleeve; a similar flexible connection firmly secured to the other of said sleeves and extending about and bearing upon the sheaves and pulleys surrounding its sleeve; segmental chambers connecting the inner end of each set of cylinders; a double-acting force-pump provided with a supply-reservoir; supply-pipes connecting the discharge of said pump with each of said segmental chambers suitable discharge-pipes connecting each of said segmental chambers with said reservoir; suitable valves for controlling the inlet and discharge of said liquid; and means for automatically operating said valves to change the flow of said liquid from a direction to and from one set of cylinders to a direction toward and from the other set of cylinders.

5. In combination with a shaft to be revolved continuously in the same direction, a pair of sleeves mounted thereon end to end and geared together to revolve in opposite directions, clutch mechanisms constructed and arranged to automatically couple said sleeves to said shaft when moving in one direction, and to uncouple the same when moving in the opposite direction; two sets of hydraulic cylinders arranged one set around and radial to the axis of each of said sleeves, pistons fitted to and movable endwise in said cylinders,

a flexible connection, as a chain, firmly attached to each of said sleeves and each arranged to be acted upon by one set of pistons to rotate its sleeve in one direction, a double-acting force-pump, a supply-reservoir, pipes and passages connecting the discharge of said pump with the inner ends of each set of cylinders, and pipes and passages connecting the inner ends of each set of cylinders with said reservoir, of a valve-casing set in a fixed position between said pump and two sets of cylinders and connected to said supply and discharge pipes, and having formed therein two ports upon each of its four sides, the two ports upon one of its sides being in axial line with the ports upon its opposite side; a plug-valve fitted to the bore of said casing and movable about its axis therein and having four transverse passages formed therethrough at right angles to its axis and at different angles to each other, and so arranged that when said plug is at one extreme of its movement about its axis two of said passages that are at right angles to each other will register with two pairs of ports in said casing while the other two pairs of ports are closed, and when said plug is moved about its axis to the other extreme of its movement, the two pairs of ports previously closed will be opened, and those before opened will be closed, whereby the liquid discharged from the pump is alternately forced into the two sets of cylinders and discharged from the opposite set of cylinders; and means for automatically moving said plug-valve about its axis when either sleeve has moved a sufficient distance about its axis in a forward direction.

6. In combination with a shaft to be revolved, a pair of sleeves mounted end to end on said shaft; a clutch mechanism carried by each of said sleeves and adapted to automatically couple its sleeve to said shaft when moved in one direction and to uncouple the same when moved in the opposite; gearing connecting said sleeves together to cause them to revolve in opposite directions the two frames 11 and 12 provided with the chambers 14 and 15 and opening 16; a plurality of cylinders 13 carried by each of said frames and communicating at their inner ends with the segmental chamber 14; a plurality of pistons 17 in the cylinders on each frame; a sheave 18 carried by each piston; the pulleys 22, 23, and 24 mounted on each of the frames 11 and 12; the chain 20 mounted upon the sheaves 18 and pulleys 22, 23, and 24 carried by the frame 11, and firmly attached at its ends to the sleeve 4; the chain 25 similarly mounted on the sheaves and pulleys on the frame 12; the valve-casing 38 mounted in a fixed position and provided with the ports 41, 42, 43, and 44; the plug-valve 45 provided with the transverse passages 46, 47, 48, and 49; the pin 72 set in said valve 45; the disk 66 provided with the tooth 67; and mounted upon and revoluble with one of said sleeves; the

lever 70 engaging at one end the pin 72 and pivoted at its other end to one end of the rod 69, provided with the tooth 68 at its other end and mounted on a suitable guide-bearing beneath the axis of said disk 66; chambered castings 50 and 61 secured to the bottom and front sides respectively of said valve-casing; the pump 53 provided with a reservoir; the pipe 52 connecting said pump to the chambered casting 50; the pipe 62 connecting said reservoir to the chambered casting 61; the pipes 36 and 39 leading respectively from the right and left hand chambers 14 to the upper ports 43 and 42 respectively; and the pipes 57 and 64 leading respectively from the chamber 14 in the right and left hand frames 11 and 12 to the ports 44 and 41 respectively in the rear face of said casing 38.

7. In combination with a shaft to be revolved, a pair of hydraulic-jack mechanisms arranged at different distances from the end of said shaft, and connecting devices between said mechanisms and said shaft, all constructed, arranged and operating to intermittently 25 and alternately act upon said shaft to move it about its axis a given distance in the same direction; a double-acting force-pump; pipes leading from said pump to both of said hydraulic-jack mechanisms; a reservoir from 30 which said pump draws its supply of liquid; return-pipes leading from each of said jack mechanisms to said reservoir; a single valve in communication with each of said pipes and constructed and arranged to be moved into 35 two different positions, and when in one po-

sition to cause the liquid from said pump to be forced into the left jack mechanism and the liquid discharged from the right jack mechanism to flow into said reservoir, and when moved into its other position, to cause 40 the liquid to be forced by said pump in the right jack mechanism and the liquid discharged from the left jack mechanism to flow into said reservoir; and means for automatically changing the position of said valve at 45 predetermined intervals.

8. In a hydraulic mechanism, the combination with two jack mechanisms; a force-pump; a reservoir; pipes connecting said pump and said reservoir to each of said jack mechanisms; the valve-casing 38 provided with the four pairs of ports 41, 42, 43 and 44, and the chambers 51, 37, 40, 58, 65, and 60, communicating with said pipes; and the single plug-valve 45 provided with the transverse passages 46, 47, 48, and 49, each arranged to register with one pair of said ports when said valve is in one or the other of its two positions; and means for automatically changing the position of said valve. 60

In testimony whereof we have signed our names to this specification, in the presence of two subscribing witnesses, on this 5th day of February, A. D. 1900.
